DESIGN FOR A TOASTER

Trace Christenson, Jr., and Warner W. Hoople,
Chicago, Ill., assignors to National Stamping
& Electric Works, Chicago, Ill., a corporation of
Illinois

Application September 3, 1940, Serial No. 94,761

Term of patent 7 years

To all whom it may concern:

Be it known that we, Trace Christenson, Jr., and Warner W. Hoople, citizens of the United States and residents of Chicago, in the county of Cook and State of Illinois, have invented a new, original, and ornamental Design for a Toaster, of which the following is a specification, reference being had to the accompanying drawing, forming part thereof.

Figure 1 is a perspective view of a toaster, showing our new design; and

Figure 2 is an end elevational view thereof.

We claim:

The ornamental design for a toaster, substantially as shown.
